UNITED STATES PATENT OFFICE.

ISRAEL V. EDGERTON, OF CHICAGO, ILLINOIS, ASSIGNOR TO PALACE POULTRY CAR COMPANY, OF CHICAGO, ILLINOIS, A CORPORATION OF ILLINOIS.

CAR VENTILATOR.

Application filed December 27, 1926. Serial No. 157,086.

This invention relates to car ventilators, having reference more particularly to ventilators used on cars for the transportation of poultry and other live stock.

5 Heretofore, so far as I am aware, ventilators of this type have consisted of hinged shutters guarding opening in the side walls of the clearstory between the running board and the roof, and opening in an outward direction. Where, as is common in poultry cars, screens are also employed under the ventilator shutters, this construction has required the attendant to climb onto the roof of the car in order to open or close the doors 10 to the ventilating openings.

One object of my present invention is to provide an improved ventilator wherein the shutters shall be capable of being opened inwardly of the car and from the interior of 20 the latter, making it unnecessary to disturb the outer screens. Another object is to provide an inwardly opening shutter ventilator with means to shed rain and prevent the latter from beating in at the joint between the 25 lower edge of the shutter and the car roof. A further object of the invention is to provide simple and improved means for supporting the shutters in open position from the roof of the clearstory.

30 Other objects and attendant advantages of the invention will be apparent to persons skilled in the art as the same becomes better understood by reference to the following detailed description, taken in connection 35 with the accompanying drawings wherein I have illustrated a practical and approved embodiment of the invention, and in which—

Fig. 1 is a vertical cross-section through the roof and clearstory of a car equipped 40 with my improvement, showing the shutters in closed position;

Fig. 2 is a similar view showing the shutters in open position;

Fig. 3 is a longitudinal vertical section, 45 broken out between its ends, on the line 3—3 of Fig. 1;

Fig. 4 is an outside elevation, broken out between its ends, of one side of the clearstory, showing the screens and the means 50 for removably mounting the latter in place.

Referring to the drawing, 10 designates the principal roof rafters supporting the purlins 11, common rafters 12 and roof sheathing 13, all as common in freight car 55 construction. 14 designates the rafters of

the clearstory consisting of suitably bent scrap iron members footed on and secured to the principal rafters 10, and in turn supporting the running board 15 attached thereto by bolts 16.

60 Portions of the side openings between the roof sheathing 13 and the running board 15 at each end of the car are normally closed by ventilator shutters; and the present invention is concerned mainly with a novel manner and means of mounting and sealing these shutters by which they can be opened inwardly from within the car and without disturbing the outside screens, where the latter are employed, and also preserving a rain-tight joint at the lower edges of the shutters. 65 17 designates the shutter board, to the inner side of which are secured a pair of U-shaped hinge members 18 formed at their upper ends with suspension loops 18'. These hinge loops are suspended from hinge straps 19 conveniently attached to the under sides of the clearstory rafters 14 by the bolts 16. Each of the hinge straps 19 is so bent as to 70 form outer and inner seats 20 and 21 for the hinge loop 18'. Suspended from and swiveled in a hanger bracket 22 (Fig. 2) attached to the running board 15 at a point about midway between the ends of an opposed pair of shutters is a T-bolt, conveniently bent to form from heavy wire and comprising a vertical stem 23 and a horizontal head 24. This T-bolt can be readily turned between a position wherein the head 24 extends longitudinally of the car, as 75 shown in Figs. 1 and 3, to a position wherein it extends transversely of the car, as shown 80 in Fig. 2.

To the inner side of each shutter 17 about 85 midway between the hinge members 18 are transverse cleats 25, which serve to stiffen the shutters and also serve as handles by which each shutter can be grasped, lifted, and its hinge loop 18' shifted between the seats 20 and 21 of the hinge straps or brackets 19. In the closed position of the shutters, the hinge loops 18' occupy the outer seats 20, 90 as shown in Fig. 1. When it is desired to open the shutters, the hinge loops are shifted 100 into the inner seats 21, they are then swung inwardly toward the central suspended T-bolts, and the heads 24 of the latter are then turned through a right angle so as to underlie and support the free edges of the shutters, in the manner clearly shown in Fig. 2. 105 110

To provide a seal against rain, snow and cinders, I attach to the inner edge of the roof sheathing 13 sheet-metal weather strips 26, the inner edges of which overhang the inner edges of the sheathing 13 and are bent upwardly, as shown at 26'. The inner side of the lower edge of each shutter is beveled or chamfered, and attached thereto is a gutter shaped lip 27 that, in the closed position 10 of the shutter, internests with the upwardly inclined edge 26' of the weather strip 26. This provides an efficient joint for excluding moisture and dirt, and in no wise interferes with the opening of the shutters, since when 15 the latter are raised to shift them to the inner seats 21, the lower edge of the shutter clears the upstanding lip 26'.

Guarding the openings opposite the respective shutters are screens 28, the rectangular frames 28' of which are removably mounted on and locked in place by J-bolts 29 mounted in the rafters 14. It will be observed that the described method and means of mounting the shutters makes it possible 25 to open and close the latter not only without disturbing the screens but without the necessity of going outside the car which, in winter weather, is both disagreeable and dangerous.

I claim—

- 30 1. In a car ventilator, the combination with inwardly swinging shutters hinged at their upper edges opposite the ventilating openings of the clearstory, of inverted T-shaped members swivelingly attached to and 35 depending from the roof of the clearstory, the heads of said T-shaped members adapted, when disposed lengthwise of the car to permit full opening of said shutters, and when disposed crosswise of the car to underlie and 40 support the free edges of said shutters.
2. In a car ventilator, in combination with the clearstory having ventilation openings in its sides, hinge brackets attached to the underside of the clearstory roof and each 45 formed with outer and inner seats, inwardly opening shutters disposed opposite the inner

sides of said openings, hinge straps attached to said shutters formed with loops engaged with said outer seats when said shutters are in closed position and shiftable to engage 50 with said inner seats when said shutters are being opened, and means for supporting said shutters in the opened position of the latter.

3. In a car ventilator, in combination with 55 the clearstory having ventilating openings in its sides, hinge brackets attached to the underside of the clearstory roof and each formed with outer and inner seats, shutters having on their upper edges hinge loops engageable with either of said seats and at 60 their lower edges outwardly overlapping the lower edges of said openings when the shutters are closed, said shutters being bodily shiftable inwardly from closed position to 65 transfer their hinge loops to said inner seats and simultaneously clear their lower edges from the lower edges of said openings, and means suspended from the clearstory roof for supporting said shutters in inwardly 70 raised position.

4. A structural combination as defined in 75 claim 3 wherein the lapping edges of the shutters and the ventilating opening are formed with interfitting weather-strips separable under a bodily upward movement of the shutter in the operation of opening the latter.

5. In a car ventilator, in combination with 80 the clearstory having ventilating openings in its sides, shutters suspended from the roof of the clearstory opposite the inner sides of said openings, outer and inner hinge sockets spaced crosswise of the clearstory on which said shutters may be interchangeably 85 hinged, said shutters in closed position hanging from the outer sockets, and in opened position hanging from the inner sockets, and means operable from the interior of the car for supporting said shutters in opened 90 position.

ISRAEL V. EDGERTON.
